UNITED STATES PATENT OFFICE

JOHN FRANKLIN SNOVER, OF JOHNSON CITY, NEW YORK

WOODWORKING MACHINE

Application filed March 11, 1927. Serial No. 174,569.

The invention has for an object to effect improvements in portable machines for use in a variety of operations in wood working, and it is also adapted for use as a permanent installation. It is a particular aim of the invention to provide a novel series of adjustments of a rotary saw or other tool whereby it may be used for making various cuts in mitering, as well as providing at the same time a machine applicable to sawing, boring, dadoing, plowing, stair routing, tenoning, shaping, molding, panel-raising, dove-tailing and other uses, with expedition and efficiency. A further aim is to provide a novel coordination of mounting elements for the attainment of the multiplicity of functions possible in my machine, as embodied. It is also a purpose to present novel structure in certain elements.

Additional objects, advantages and features of invention reside in the construction, arrangement and combination of parts, as will be understood from the following description and accompanying drawings, wherein

Figure 1 is a side elevation of my invention.

Figure 2 is a similar view of the horizontal arm swung toward an observer, and the motor device in a different position.

Figure 3 is a horizontal section of the standard and base of the cross arm.

Figure 4 is a fragmentary section of the motor mounting.

Figure 5 is an inner side view of the carriage body.

Figure 6 is a detail of the screw release.

Figure 7 is the operating crank.

There is illustrated formally a portion of a bench 10, upon which my invention may be mounted. At a suitable distance inwardly from the front of the bench a circular base plate 11 is bolted, having a central circular boss 12 thereon smoothly finished, fitting a corresponding smoothly finished recess in the bottom of an upright or standard 13, substantially U-shaped in cross section but having guide flanges 14 at the edges of its open side, extending throughout its length in a vertical plane. The body of the upright is offset so that the flanges 14 lie in a plane closely adjacent the axis of the boss 12. The plate 11 im-

mediately adjacent the boss is smoothly finished in a plane at right angles to the axis of the boss to support the standard thereon revolubly, and a bolt 15 is engaged through the plate 11 and the lower part of the standard, to hold the latter securely and revolubly upon the plate 11. In the standard 13 and extending from closely adjacent the lower end thereof to the top, there is a screw 16 having its lower end revolubly tenoned in a transverse plate 17, formed integrally between the sides of the standard, the upper end of the screw being journaled in a corresponding top portion 18 of the standard, and formed with an angular head 19 disposed above the standard and adapted to receive a crank by which the screw may be operated. This screw is preferably formed with threads having a pitch of one-eighth of an inch, that is, eight threads to the inch, so that one turn of the screw will represent an adjustment of a member moved thereby of one-eighth of an inch, for convenience in figuring positions of cuts in accordance to standard English measurements.

Vertically adjustable upon the standard 13, there is a cross arm 21, similar in construction to the standard 13 itself, although it may be made somewhat lighter in weight, if desired, the principal difference in the present instance being a modification in the mounting of a horizontal screw 22 therein similar to the screw 16 before mentioned. The cross arm is mounted upon a rectangular plate 23, which is set slidably against the front faces of the flanges 14, and held thereto by means of flange plates 24 bolted to the plate 23 at each side and overlapping the flanges 14, as shown in Figures 3 and 4. The arm 21 is mounted upon the plate 23 in a manner similar to the mounting of the standard on the base 11, except that the boss 25 is formed on the base of the arm 21 instead of in the plate 23, the latter being formed with a corresponding recess to receive the boss. Also in the present instance, the bolt 26 has a circular recess in its hexagon head 27 which is presented outwardly and within the arm 21, the inner end of the screw 22 being set revolubly in this recess, so that the bolt serves as a bearing for the screw as 100

well as holding the arm 21 revolubly upon the plate 23. The screw is preferably tenoned, so that a nut 28 thereon at the inner side of the plate 23 and within the standard will hold 5 the bolt fixedly against the plate 23 and also avoiding locking of the base of the arm against rotation on the plate 23.

The plate 23 is provided with ears 29 projecting into the standard 13 at the upper and lower parts of the plate 23, apertured and 10 interiorly threaded to receive the screw 16, whereby upon rotation of the screw the plate 23 will be moved vertically upward or downward. The screw is set inwardly from the 15 axis of rotation of the standard, so that it clears the bolt 26 and nut 28. Upon the arm 21 there is mounted a motor carriage including parts corresponding to those 23 and 24.

In place of the ears 29 on the plate 23, the 20 corresponding plate 30 of the carriage has a hand screw or lever operated screw 31, tenoned in the plate 30, the tenon projecting outwardly and carrying the lever. On the inner part of the screw there is provided a 25 nut 32 snugly slidable between ears 33 on the inner side of the plate 30, the nut having a segmental internal worm on the side toward the screw 22, so that upon rotation of the screw 31 in one direction, the nut will be 30 pressed against the screw 22, and thereby rotation of the latter will move the carriage; and upon reverse rotation of the screw 31, the nut will be drawn out of mesh with the screw 22, so that the carriage will then be 35 free to reciprocate independently of the screw 22. A motor 35 is provided, having a base 36 fitted thereto and secured to the carriage in the same manner that the arm 21 is secured to the plate 23 so that the motor may be rotated 40 on the carriage on an axis at right angles to both screw 22 and shaft 37 of the motor. The shaft 37 may have mounted on one end a suitable rotary saw 40 with any quick-release means, while the other end of 45 the shaft may be provided with a chuck 41 to carry cutters 42, or other tools as required.

If desired, clamp screws 43 may be provided to hold the standard 13 in adjusted 50 position on the base 11; another to hold the arm against rotation on the plate 23, and another to secure the base 36 of the motor fixed on the carriage plate 30.

The base 11, the plate 23 and the corresponding part of the carriage plate 30 preferably have one or more pointers 44 immediately adjacent the edge of the rotating members secured thereon respectively, and the base of the standard 13, the arm 21 and the base 36 of the motor are each formed 55 with graduated scales 45, which, in conjunction with the pointers 44 will enable the adjustment accurately of the saw or other tool on the motor shaft in various required angles with respect to the work.

60 In use, the device may be used in numerous

ways which will readily suggest themselves to those required to do the kinds of work first outlined herein. One simple manner of use consists in adjusting a timber on the bench 70 10 on a predetermined line with respect to the base of the standard 12, and the scale and pointer thereon, or with respect to a vertical plane coincident with the axis of the arm 21, then adjusting the motor on its carriage to bring the saw into a plane having 75 the desired angle to the longitudinal axis of the work, and then lowering the arm by operation of the screw 16 until the desired cut has been made, then raising the arm again 80 and proceeding with other cuts by the necessary change of position of the motor on the carriage, or shift of the carriage on the arm, or shifting of the arm 21, or a combination 85 of these adjustments. The arm 21 may be rotated to bring the carriage 30 into a vertical 90 plane at one side of the arm, and the motor then rotated on the carriage until the saw is presented at a peculiar desired angle to the vertical or horizontal, the arm 21 lowered until the saw is close to the bench top, and a timber then moved slidably and longitudinally on the bench into engagement with the saw, whereby the timber may be cut with one longitudinal face at a particular desired 95 angle to another face of the piece. Also, the device may be employed as an efficient and easily operated cross cut and miter saw, as well as permitting miters to be similarly 100 cut by simple adjustments of the arm centrally or to the right or left over the bench, releasing the screw 22 and moving the carriage by hand upon the arm 21 while the timbers to be cut are simply held stationary 105 upon the bench in the path of the saw. Various operations with other tools may be performed with such and other adjustments.

I claim:

In a woodworking machine, the combination of a base; a standard rotatably mounted on said base; a plate vertically slidably on said standard; a tool supporting arm U-shaped in cross-section; a trackway formed by the edges of said arm; flanges extending across the ends of said arm; a pintle bolt on said plate and received through one of 110 said flanges to revolubly mount said arm; a revoluble screw journaled in said bolt and the other flange and positioned in the plane of said trackway; a carriage slidably mounted on said trackway; means connecting said carriage and said screw whereby said carriage is moved by the revolution of said screw; and a motor driven tool rotatably mounted on 115 said carriage.

In testimony whereof I affix my signature. 125
JOHN FRANKLIN SNOVER.
